UNITED STATES PATENT OFFICE.

DAVID H. COLES, OF BROOKLYN, NEW YORK.

SAFETY TACK-LIFTER.

1,130,147.

Specification of Letters Patent.

Patented Mar. 2, 1915.

Application filed July 17, 1914. Serial No. 851,444.

To all whom it may concern:

Be it known that I, DAVID H. COLES, a citizen of the United States of America, and a resident of Brooklyn, county of Kings, 5 and State of New York, have invented certain new and useful Improvements in Safety Tack-Lifters, of which the following is a specification.

This invention has reference to improvements in tools.

It pertains particularly to a safety tool for lifting or raising short, sharp-pointed tacks, nails or pins.

The safety tack lifter is designed and constructed for the purpose of protecting the hand, the fingers and especially the knuckles or joints of the fingers located between the metacarpal bone and the first phalanx, against injury.

When some one lifts or raises tacks with ordinary tools a slight scratch or wound may result and cause even blood poisoning. For this reason my novel lifter is provided with a safety device and also with means for 20 increasing the leverage.

The novel safety device comprises essentially a curved shield extending from the handle downwardly and forming a rest for the index finger and thumb while the other 30 fingers grip the handle. The shield has on its lower portion an inward curved extension which forms a rest when a tack is lifted and prevents damage to the floor, carpet or the like. This curved rest coöperates with 35 the means for increasing the leverage at the front portion of the tool.

In order to render the invention entirely clear reference is had to the accompanying drawing on which:

40 Figure 1 represents in top plan view a safety tack lifter which embodies in desirable form the present improvements. Fig. 2 is a side elevation of the same.

Similar characters of reference denote 45 like parts in all the figures.

In the drawing *a* represents the handle which supports the tack lifter. Part of the shank *b* of the lifter passes through the handle in the usual manner for the purpose of 50 securing it. The front portion of the shank *b* is divided forming an angular flanch *b*¹ which extends in an upward direction as shown in Fig. 2. The flanch *b*¹ spreads out and gradually decreases in thickness toward 55 its outer end. It has a slit *c* whereby the flanch becomes dove-tail shaped forming

two short lifting members *b*² *b*³. The slit *c* is angular and somewhat beveled off as shown at *c*¹. The slitted section of the tool is placed under the head of the tack when 60 the same is to be lifted.

In order to increase the leverage of the tool its front portion, adjoining the upwardly bent operative part has formed on the lower surface a rounded off extension *d*. 65 When the operative part of the tool has been placed under the head of the tack extension *d* will rest on the floor or carpet and facilitate the lifting of the tack. This protruding portion *d* coöperates with the safety 70 device of the tool to be described hereinafter.

At the inner end of the handle a protective shield *e* is provided which is of peculiar construction and has formed thereon a 75 lower curved portion *e*¹. The shield is secured at a right angle to the tool. It is curved and hollowed out forming a section of a sphere so as to provide a convenient rest for the fingers. The bottom portion *e*¹ 80 of the shield is curved inwardly as shown. This lower curved portion *e*¹ comes in contact with the floor or carpet during the operation of the tool and as it is inwardly curved it rests flat on the carpet and cannot 85 damage same.

When a tack is to be lifted the slitted operative portion at the front end of the tool is shifted under the head of the tack and a slight pressure exerted in the downward direction whereby its protruding portion *d* 90 comes down upon the carpet or floor. When pressing down a little farther the curved portion *e*¹ of the safety shield *e* reaches the carpet or floor thus coöperating with the 95 protruding portion *d* at the bottom of the operative portion. It is evident that the operative's fingers or hands cannot be injured should the tool slip, because the shield protects the fingers when the slipping tool 100 moves forward and the lower curved portion *e*¹ of the shield protects the fingers against injury on the floor or any object thereon. In this manner the inward curved portion *e*¹ performs two functions, first it 105 aids in increasing the leverage of the tool and second it protects the lower portions of the fingers and hand when the tool slips.

I claim as my invention:

1. A safety tack lifter comprising essentially a handle, a shank secured in the said handle, a tack lifter formed on the front end

of said shank, and a curved shield mounted on the inner end of the handle and having an integral inwardly curved extension on its bottom portion.

- 5 2. A safety tack lifter comprising essentially a handle, a shank secured in the said handle, a tack lifter formed on the front end of said shank, bent in an upward direction and having a rounded off extension on the 10 lower surface adjoining the shank, and a curved shield mounted on the inner end of the handle and having an integral inwardly curved extension.

3. In a safety tack lifter having a han-

dle on one end and a tack lifter at the other 15 end bent in an upward direction, an extension on the lower inner end surface on said lifter and a curved protective shield mounted on the inner end of the handle and having an integral inwardly curved extension 20 on its bottom portion.

Signed at New York, N. Y., this 15th day of July, 1914.

DAVID H. COLES.
